UNITED STATES PATENT OFFICE

107,880

DESIGN FOR A MATTRESS

Max Marsack, Milwaukee, Wis., assignor to Li-
On Bedding Company, Milwaukee, Wis., a corporation of Wisconsin

Application August 14, 1937, Serial No. 71,083

Term of patent 14 years

To all whom it may concern:

Be it known that I, Max Marsack, a citizen of the United States, residing at Milwaukee, in the county of Milwaukee and State of Wisconsin, have invented a new, original, and ornamental Design for a Mattress, of which the following is a specification, reference being had to the accompanying drawing, forming a part thereof.

Referring to the drawing:

The figure is a perspective view of a mattress embodying the design.

I claim:

The ornamental design for a mattress, as shown.

MAX MARSACK.
